UNITED STATES PATENT OFFICE.

MARY A. HERR, OF CAPE GIRARDEAU, MISSOURI.

DESIGN FOR A CHILD'S KNIFE-BLADE.

SPECIFICATION forming part of Design No. 34,401, dated April 23, 1901.

Application filed March 23, 1901. Serial No. 52,660. Term of patent 7 years.

To all whom it may concern:

Be it known that I, MARY A. HERR, a citizen of the United States, and a resident of Cape Girardeau, in the county of Cape Girardeau and State of Missouri, have invented and produced a new and original Design for a Child's Knife-Blade, of which the following is a full, clear, and exact description.

Reference is to be had to the accompanying drawings, forming a part of this specification, in which similar characters of reference indicate corresponding parts in both the figures.

Figure 1 is a perspective view of a child's knife-blade, showing my design; and Fig. 2 is an edge view of the same.

The leading feature of my design for a child's knife-blade consists of a body portion sharpened at one edge, one end having a plate or tang-like projection, while the other end is rounded or carried in a curved line from the back to the sharp edge of the body and has a portion extended beyond the line of the sharp edge.

Referring particularly to the drawings, 1 designates the body portion of the knife-blade, 25 which is formed with one sharp edge, and at one end of the body is a tang-like projection 2, while the other end is curved from the back to the sharpened edge of the body, and a portion 3 of this curved end is extended below 30 the line of the sharpened edge, and the connection between said projected portion and the sharpened edge is reentrant, as at 4.

Having thus described my invention, I claim as new and desire to secure by Letters 35 Patent—

The design for a child's knife-blade, as herein shown and described.

In testimony whereof I have signed my name to this specification in the presence of 40 two subscribing witnesses.

MARY A. HERR.
